UNITED STATES PATENT OFFICE.

EDWIN S. LEAYCRAFT, OF NEW YORK, N. Y.

PNEUMATIC-TUBE CARRIER.

SPECIFICATION forming part of Letters Patent No. 242,459, dated June 7, 1881.

Application filed November 18, 1880. (No model.)

To all whom it may concern:

Be it known that I, EDWIN S. LEAYCRAFT, a resident of the city, county, and State of New York, and a citizen of the United States, 5 have invented a new and useful Improvement in Parcel-Carriers for Pneumatic Parcel-Dispatch Tubes, of which the following, taken in connection with the accompanying drawings, is a full, clear, and accurate description.

10 The object of my improvement is to provide a new and improved parcel-carrier for pneumatic parcel-dispatch tubes, which is adapted especially but not exclusively for use in the pneumatic tube shown and described in my 15 Letters Patent No. 178,784, granted to me June 13, 1876, for pneumatic parcel-dispatch tubes.

In the drawings, Figure 1 represents a plan view of my improved parcel-carrier when open. Fig. 2 represents a plan view of the same when 20 closed. Fig. 3 shows a sectional view of the end of the same, when open, on line *xx*, Fig. 1. Fig. 4 shows a sectional view of the end of the same, when closed, on line *yy*, Fig. 2.

25 My carrier is formed of two cylindrical pieces, A and B, of any suitable material and of any size desired, hinged together longitudinally by the hinge C.

At each end of the carrier is a separate compartment, *c*. These compartments *c* are provided with a spiral or elliptical spring, *D*, or 30 other elastic material, which is secured in the said compartments *c*. This spring *D* will act with equal force either side of the center of the hinge C, and by its action will hold the parts 35 A B of the carrier open, or hold them tightly together when closed.

The function of the compartments *c* at the ends of the carrier is to serve each as a covered receptacle for its spring *D*, so that in the 40 operation of the latter, in opening and closing the door, the parcels in the carrier will not interfere with the action of the springs. An arm, *d*, is secured to the cylindrical part A

at one end, and to the pin *a* on the outer end of said arm, and beyond the hinge C the U- 45 shaped end of the spring *D* is pivoted, the opposite end of said spring being pivoted to the part B, by which construction the spring will hold the part B open or closed.

Secured to the compartments *c* of the parts 50 A and B of the parcel-carriers are the pads *G*, preferably made in three parts, the part next to the compartment *c* being preferably a tempered-steel disk, *h*, with an angular flange. These disks *h* are secured to the parts *g* of the 55 said pads *G*. These parts *g* are made preferably of leather, and are secured to the end parts of the said pads *G*, which are made preferably of conical shape, and of felt. The object of these pads is to prevent the carrier from 60 being injured or its momentum retarded in its passage through the pneumatic tubes, and also to prevent the carrier in its ejection from the ejecting-valve of the pneumatic tube from 65 injuring the valve. These pads *G* also keep the carrier closely locked in its passage through the tube, and prevent any injury to it.

Having thus described my invention, what I claim, and desire to secure by Letters Patent, is—

1. The parcel-carrier composed of the sections A and B, provided with separate compartments *c* and springs *D*.
2. The pads *G*, provided with the parts *g* and disks *h*, and in three sections, in combination with the sections A and B of the carrier.
3. The parcel-carrier composed of the two sections A and B, and provided with the separate compartments *c* and springs *D* and pads *G*.

In testimony whereof I have hereunto set my hand this 16th day of November, 1880.

E. S. LEAYCRAFT.

In presence of—

CHARLES G. COE,
LOUIS W. FROST.
